CLAIM

The ornamental design for a length measuring apparatus, as shown and described.

DESCRIPTION

1. Length measuring apparatus

1.1 : Perspective

1.2 : Front

1.3 : Back

1.4 : Top

1.5 : Bottom

1.6 : Left

1.7 : Right

The parts shown by means of broken lines in the reproductions are not part of the claimed design.

1 Claim, 7 Drawing Sheets(56)
